WASHINGTON.

COFFEE CAN OR THE LIKE.

Application filed October 9, 1924. Serial No. 742,607.

This invention relates to improvements in coffee cans, or the like, and more particularly to cans in which it is intended that the contents be vacuum packed; it being the 5 principal object of this invention to provide a can, or container, having the top or end wall equipped with a sealed opening through which the contents may be emptied from the can and which has a slide valve 10 operable to close the said opening as a means for protecting the contents of the can after the seal has been removed.

Another object of the invention is to provide a container of the above character having an opening in its end wall as above stated, with a slide valve disposed within the can and movable from and over said opening by means of a strip of metal that is attached to the valve and which extends 20 through a slot in the end wall with its outer end covered by the sealing plate and adapted to be exposed only by the removal of said seal.

Other objects of the invention reside in 25 the various details of construction and combination of parts embodied in the invention as will hereinafter be described.

In accomplishing these and other objects of the invention, we have provided the improved details of construction, the preferred forms of which are illustrated in the accompanying drawings, wherein—

Figure 1 is a perspective view of a can equipped with a valve discharge opening in 35 accordance with details of the present invention, showing the valve partly open and contents being poured from the can.

Figure 2 is a sectional detail view illustrating the disposition of the slide valve below the sealed opening in the can top, the means for supporting the slide and means whereby it is moved between open and closed positions.

Figure 3 is a perspective view of the top 45 or end of the can showing the seal applied over the opening.

Figure 4 is a view showing the seal partly removed.

Figure 5 is a similar view with the seal 50 removed from the opening and the valve partly opened.

Figure 6 is a perspective view in which a part of the can wall is broken away for the purpose of showing the under side of

the cover and plate attached thereto for 55 slidably supporting the valve.

Figure 7 is a perspective view illustrating an alternative method of supporting the slide valve.

Referring more in detail to the several 60 views of the drawings—

1 designates what may be a can or container of that character in which coffee, or the like, is packed for sale; the can here shown being of cylindrical form and having 65 a top, or end wall 2 sealed to the body in an air tight connection. Formed in the top wall adjacent to the edge or periphery of the can is an opening 4 through which the contents of the can may be poured, as illustrated in Figure 1; the opening preferably being substantially of triangular outline and extending in a point toward the center of the top.

Located beneath the opening 4 for 70 slid- able movement from and across the same in the radial direction of the top, is a valve plate 5 supported by means of plate 6 that is soldered or otherwise secured at its ends to the under side of the top and which provides a space between its central portion and the under side of the top within which the valve plate may slide; the valve is held securely and closely against the under side 75 of the top and effectively closes the opening.

The means provided for shifting the valve plate 5 between open and closed positions consists of a thin flexible metal strip 7 having one end attached to the top face of the valve near the outer edge of the latter, by 80 means of spot welding or soldering as indicated at 8 in Figure 5, and having its opposite end portion extended through a slot 9 in the can top wall located in a radial line 85 between the center of the top and the nearest point of the opening 4. Before the sealing plate, presently described, has been removed from over the opening, the exposed end of the strip 7 is turned down flat against the top wall, as shown in Figure 4, but after 90 the seal has been removed, it may be turned up, as in Figure 5, and the valve operated 95 between open and closed positions thereby.

As was previously stated, the present construction is intended to be used in connection with cans or containers in which coffee, or the like, is vacuum packed, and in order 100 to make the cans suitable for this method of

packing, we have placed a sealing plate 10 over the opening 4 and have extended it to cover the slot 9 and back turned end of the strip 7. This sealing plate is affixed to the can top in an air tight joint by means of a soft solder, or the like. It is tapered toward the center of the can to a narrow end portion 11 that is left loose and by means of which the plate may be pulled loose to uncover the opening.

In Figure 7 we have disclosed a slightly modified construction in which the opening 4 is of rectangular form and the metal that is stamped from the top in forming the opening is turned outwardly and then inwardly along opposite edges of the opening to form guides 12 in which the valve plate 5 is slidably supported. This construction eliminates the use of the plate 6 as shown in Figure 6 of the drawings.

In assembling the parts of the can, the top is first provided with the opening 4 and slot 9, the plate 6 attached to the under side of the top and valve plate placed in position to cover the opening. The strip 7 is then projected through the slot 9, its inner end attached to the valve plate and its outer end turned down against the top. The sealing plate 10 is then applied over the opening and sealed to the top. The tops, so equipped, are then applied to the filled can bodies, while under vacuum.

When it is desired to use the contents of a can, the sealing strip is removed from over the opening 4 by grasping the end 11 and pulling upwardly and outwardly thereon to tear it loose. A suitable key can be provided for this if necessary. Then the exposed end of the strip 7 is bent upwardly to provide a finger hold and valve adjusted to open position thereby.

While we have described and illustrated this construction in connection with coffee cans, it is not intended that it be limited only to that particular use as it is readily apparent that such construction is applicable to va-

rious kinds of cans or containers in which the contents may or may not be vacuum sealed.

It is further apparent that various details in construction and combination of parts, shape, proportion and mode of operation could be varied without departing from the spirit of the invention and for this reason we do not wish to be confined only to the details herein illustrated.

Having thus described our invention what we claim as new therein and desire to secure by Letters Patent, is:

1. A container of the character described having a discharge opening in a wall thereof and a slot adjacent said opening, a valve supporting plate secured to the inside of said wall, a valve plate slidably supported by said supporting plate and adapted for movement from and across the said opening, a flexible strip attached to the valve plate and extended through said slot by means of which said valve plate may be shifted and a sealing plate overlying the opening, slot and end of said strip and removably sealed in an air tight joint to the container wall.

2. As an article of manufacture, a can cover having a discharge opening near its periphery and a slot adjacent said opening, a valve supporting plate secured to the under side of said cover, a valve plate slidably supported thereby for movement from and across the said opening, a flexible metal strip attached at one end to the valve and having its other end projected through said slot and turned down against the said cover, and a plate removably sealed to the top of the cover to overlie said opening and slot and having a detached end portion by means of which the plate may be pulled loose from the top.

Signed at Seattle, King County, Washington, this 2nd day of October, 1924.

GEORGE H. TURPEL.
ALBERT O. JOHNSON.
